UNITED STATES PATENT OFFICE.

JOSEPH N. HADJISKY, OF DETROIT, MICHIGAN.

GAS-COMPRESSOR.

1,387,259.

Specification of Letters Patent. Patented Aug. 9, 1921.

Application filed June 23, 1919. Serial No. 305,971.

To all whom it may concern:

Be it known that I, JOSEPH N. HADJISKY, a subject of the King of Bulgaria, residing at Detroit, in the county of Wayne and State 5 of Michigan, have invented certain new and useful Improvements in Gas-Compressors, of which the following is a specification, reference being had therein to the accompanying drawings.

10 The invention relates to gas compressors of that type in which compressive force is applied to the gas or vapor to be compressed hydraulically. It is the object of the invention to obtain a simple and efficient apparatus and one in which clearances are reduced to the minimum so as to be capable of attaining high compression. Further advantages of my improved construction are absence of forcibly wearing parts and higher 15 volumetric efficiency.

Generally described, my improvement consists in a chambered casing having valve-controlled gas inlet and outlet connections, together with hydraulic means for alternately filling and emptying the chamber 25 with a liquid. Preferably there are provided two such chambers which are alternately filled and emptied, the liquid being pumped out from one and into the other and there 30 is further preferably provided reversing means automatically operated upon the completion of the displacement of the compressed gas.

In the drawings I have omitted the hydraulic pump, which may be of any suitable construction, and have illustrated the gas compression apparatus and controlling mechanism.

Figure 1 is a sectional plan view; 40 Fig. 2 is a sectional side elevation; Fig. 3 is a transverse section substantially on line 3—3 of Fig. 2.

In detail, my improved apparatus comprises a casing 7 which is divided by a partition 7^a into two compartments A and B. In the lower portion of the casing 7 is a liquid-controlling valve 26, preferably of the rotary oscillatory type and which controls 45 passages E, F, C and D. The passage E is connected with the suction conduit 23 of the liquid pump (not shown), and the passage F is connected with the discharge end 27 of said pump. The passage C communicates with the chamber A and the passage D 50 with the chamber B. The construction and arrangement of the valve is such that one of the chambers A and B is connected by the passage E with the discharge end of the pump, while the other of said chambers is simultaneously connected by the passage F 60 with the suction conduit of the pump, so that the liquid is drawn out from the one chamber and forced into the other. Also by movement of the valve the connections are reversed and thus the liquid may be alternately transferred from one chamber to the other. 65

At the upper end of the casing each of the chambers A and B is provided with a gas inlet conduit 1 and gas outlet conduit 2, controlled respectively by the automatic valves 22 and 19. Adjacent to the outlet valve 19 is a cylinder containing a hollow piston 4 with a float 5 arranged in the chamber there- 70 within. The end of the piston is provided with a series of ports 20 which are normally open, but are sealed upon the rise of the float 5 into contact with the head of the piston. The piston 4 is connected by a rod 8 with an operating mechanism for rotating 75 the valve 26, this comprising a rack bar 10 engaging a pinion 14 which in turn is in mesh with the gear 13 on the valve 26. The arrangement is such that when the piston 4 in one of the chambers, A and B, is moved 80 upward, it will lift the rack 10 and rotatably actuate the valve 26 so as to reverse the 85 connections of the liquid pump to the chambers.

In operation, assuming the parts in the 90 position shown in Fig. 2, the chamber B is connected by the valve 26 with the discharge conduit 27 of the liquid pump (not shown), while the chamber A is connected with the suction conduit 23 of said pump. Also as- 95 suming that the chamber A is filled with liquid and the chamber B is filled with gas, it will be evident that upon the opera- 100 tion of the pump liquid will be withdrawn from the chamber A and forced into the chamber B. This will produce a vacuum in the chamber A which is filled by the passage of gas in through the conduit 1 and past the automatic valve 22. Also the pres- 105 sure of the liquid entering the chamber B will compress the gas therein until it at- 110 tains a pressure which overcomes the resist- 115 ance of the valve 19 and back pressure from the compressed gas, whereupon said valve 19 will open and permit the compressed gas to be forced outward through the conduit 2. At the completion of the filling of the cham-

ber B with liquid the float 5 will be raised against the ports 20 in the piston 4 and upon the sealing of said ports the pressure of the liquid against the float and piston will lift 5 the latter. This will communicate motion through the rod 8 to the rack 10 operating the pinions 13 and 14 and reversing the valve 26, so that the chamber B will be connected with the suction of the liquid pump and the 10 chamber A with the discharge end of said pump. The liquid will then be withdrawn from the chamber B, creating a vacuum which draws in a new supply of gas through the inlet 1, while in the chamber A the pressure 15 of the liquid will compress the gas finally expelling it from the chamber, as just described. This cycle will be repeated as long as the pump is in operation.

Some of the advantages of my improved 20 construction are; first, it eliminates many of the moving parts so common to the reciprocating type of compressor; second, it reduces much cost by using very few highly finished parts; third, the operation is silent; 25 fourth, the liquid seal prevents leakage unavoidable with a mechanical piston; fifth, there are no parts to wear; and sixth, lubrication is automatic.

What I claim as my invention is:

30 1. A gas compressor comprising a casing provided with a pair of compartments each having a gas inlet and a gas outlet, and with a liquid outlet and a liquid inlet common to both compartments, means in each compartment adapted to automatically seal the gas outlet thereof when liquid reaches a predetermined height in the compartment, and a single liquid controlling member operatively connected to each gas outlet sealing 40 means and adapted to throw a compartment into communication with the liquid outlet when the gas outlet thereof is sealed, and to simultaneously connect the other compartment with the liquid inlet.

45 2. A gas compressor comprising a pair of compartments each having a gas inlet and a gas outlet, and with a liquid intake and a liquid outlet which are common to both compartments, liquid controlling means adapted to throw the compartments alternately into communication with the liquid inlet and outlet respectively and float controlled means at each gas outlet adapted to seal the latter when the companion compartment is liquid filled and connected to the liquid controlling means and arranged to operate the latter to 50 throw the same compartments into communication with said outlet and to connect the other compartment with the liquid filled inlet.

60 3. A gas compressor comprising a casing provided with a pair of compartments each having a gas inlet controlled by an automatic outwardly seating valve and a gas outlet controlled by an automatic inwardly seat-

ing valve and with a liquid intake and a liquid outlet each common to both compartments, a liquid controlling valve adapted to throw the compartments alternately into communication with the liquid inlet and outlet respectively, a float controlled valve for each gas outlet adapted to seal the latter when the companion compartment is liquid-filled and connected to the liquid controlling valve whereby the latter is shifted to throw the said compartment into communication with the liquid outlet and to connect the other compartment with the liquid inlet.

4. A gas compressor comprising a casing 80 with a pair of compartments each with a gas inlet provided with an automatic check valve and a gas outlet provided with an automatic check valve, and with a liquid intake and a liquid outlet each common to both compartments, a liquid controlling valve adapted to throw the chambers alternately into communication with the liquid inlet and outlet respectively, a float controlled valve for each gas outlet adapted to seal the latter when 85 the companion compartment is liquid filled, and mechanism connecting each float controlled valve with the liquid controlling valve and moving the latter to throw the companion compartment into communication with the liquid outlet when the float controlled valve seals the gas outlet.

5. A gas compressor comprising a casing provided with a pair of compartments each having a gas inlet controlled by an automatic 100 outwardly seating valve and a gas outlet controlled by an automatic inwardly seating valve, and with a liquid intake and a liquid outlet each common to both compartments, a liquid controlling valve adapted to throw 105 the chambers alternately into communication with the liquid inlet and liquid outlet respectively, a piston valve for each gas outlet adapted to seal the latter when at the upper end of its throw, a float in the piston closure of said valve for throwing the latter into closed position when the companion compartment is liquid filled, and means connecting the piston valve and liquid controlling valve and operating the latter to 110 throw the said compartment into communication with the liquid outlet when the piston valve is closed.

6. A gas compressor comprising a casing provided with a pair of compartments each having a check valved gas inlet and a check valved gas outlet, and with a liquid inlet and a liquid outlet each common to both compartments, a rotatable liquid controlling valve journaled in the casing and adapted to 120 throw the compartments alternately into communication with the liquid inlet and liquid outlet respectively and a float controlled valve for each gas outlet adapted to seal the latter when the companion compartment 125 is liquid filled.

ment is liquid filled and connected to the liquid controlling valve to shift the latter whereby the outlet of the casing is placed in communication with the companion compartment when the gas outlet float is closed.

7. A gas compressor comprising a casing provided with a pair of compartments each having a check valved gas inlet and a check valved gas outlet and with a liquid intake 10 and a liquid outlet each common to both compartments, a rotatable liquid controlling valve journaled in the casing and adapted to throw the compartments alternatively into communication with the liquid inlet and liquid outlet respectively, a float controlled valve for each gas outlet adapted to seal the latter when the companion compartment is liquid filled and rack and pinion connections between each float valve and the liquid controlled valve for so moving the latter that each compartment is connected with the liquid outlet when the gas outlet of such compartment is closed by the float valve.

8. A gas compressor comprising a casing 25 provided with a pair of compartments each having a gas inlet and a gas outlet, and with a liquid intake and a liquid outlet each common to both compartments, a liquid controlling valve adapted to throw the compartments alternately into communication with the liquid inlet and the liquid outlet respectively, a valve for each gas outlet consisting of a cylinder having a discharge opening through the head in communication with the 35 gas outlet and a piston closure reciprocable in

the cylinder provided with ports in the head thereof adapted to be sealed when the closure contacts with the cylinder head, and a float in the piston adapted to move the latter to closed position when the companion compartment is liquid filled, and means connecting the piston and the liquid controlling valve and so moving the latter when the piston closure is seated that the companion compartment is in communication with the liquid 40 outlet of the casing.

9. A gas compressor comprising a casing provided with a pair of compartments each having a gas inlet controlled by an automatic outwardly seating valve, and a gas 45 outlet, a valve for each gas outlet consisting of a cylinder mounted in the casing and ported through the head for communication with the gas outlet, an inwardly seating check valve in the cylinder head, a piston 50 closure in the cylinder provided with ports through the head thereof adapted to be sealed against the cylinder head, a float in the piston adapted to move the latter to closed position when the companion compartment is liquid filled, a rack reciprocated by the piston, a pinion operated by the rack and a liquid controlling valve journaled in the casing and rotated by the pinion to throw the companion compartment into communication with the liquid outlet when the piston 55 closure is seated.

In testimony whereof I affix my signature.

JOSEPH N. HADJISKY.
